ALEXANDER MCLEAN NICOLSON, OF NEW YORK, N. Y., ASSIGNEE, BY MESNE ASSIGNMENTS, TO FEDERAL TELEGRAPH COMPANY, A CORPORATION OF CALIFORNIA

DOUBLE REENTRANT CONE LOUD SPEAKER

Application filed March 17, 1927. Serial No. 175,989.

This invention relates to apparatus for reversibly producing sound from electrical oscillations corresponding thereto, and more particularly to such apparatus usually designated as "loud speakers," adapted to reproduce sound comparable in quality and intensity with the original sounds to be reproduced.

It is an object of this invention to provide a diaphragm having a plurality of parts or active sound radiating elements, front and rear, separated by a distance considerably greater than the thickness of the material constituting the diaphragm.

It is a further object of this invention to provide such apparatus in which the driving mechanism is mounted and contained entirely in the space between the front and rear surface of the diaphragm. It is still a further object of this invention to provide such apparatus in which a piezo-electric crystal device or a plurality of such devices are used in the diaphragm.

The features of novelty which I believe to be characteristic of my invention are set forth with particularity in the appended claims. My invention itself, however, both as to its fundamental principles and as to its practical application will best be understood by reference to the specification and accompanying drawings, in which:

Figures 1 and 2 are respectively front and side elevations of one form of apparatus according to my invention, the latter figure being partly in section;

Fig. 3 is a top plan view of the same, partly in section;

Fig. 4 is a front elevation of a modified form of apparatus according to my invention.

Fig. 5 is a top plan view partly in section thereof.

In accordance with my invention, I provide a plurality of conical diaphragms of suitable material, such as paper, cardboard, wood, composition, or metal if desired. The diaphragms are constructed so as to have the same diameter at the periphery but different altitudes, and are mounted preferably with their peripheries cemented or otherwise se-

cured together so to form a single unit. The difference in altitude is so chosen that a space is formed between the apexes, which are disposed on the same side of the peripheral plane, and the driving means is mounted 55 within this space.

In its simplest form, the driving means may comprise a piezo-electric crystal provided with a stress plate and driving rod connected to the apexes of the diaphragm, but it 60 will be clear that other means may be used in place of the piezo-electric crystal, such for example, as a driving unit of the electro-magnetic type. When electrical oscillations are supplied to the piezo-electric crystal device, 65 vibrations corresponding thereto are produced as is well known in the art.

These vibrations are transmitted to the apexes of the cones constituting the diaphragm and set up stress waves in the material, which travel from the apex outwardly toward the peripheries. It will be noted that since the paths which must be traversed by the stress waves on the inner and outer faces of the diaphragm are dissimilar in 75 length, the vibrations arriving at the periphery may be out of phase by a certain amount, and under these conditions a different type of vibration will be obtained and a different frequency response will be obtained from that which would be obtained from a single diaphragm. It is also to be noted that the inclusion of the air in the confined space between the diaphragms may act 80 as a resonance chamber which will react 85 upon the diaphragm to modify its characteristics.

In accordance with another form of my invention, I provide for driving one of the diaphragms, for example, the outer one at a 90 plurality of points other than the apex thereof in the manner described in my co-pending application entitled "Eccentric drive cone loud speaker", Serial No. 174,493, filed Mar. 11, 1927, thus producing a different 95 mode of vibration of the diaphragm, and a different frequency response.

In this arrangement, I may provide a plurality of piezo-electric crystals contained 100 within the diaphragm, each of which may be

connected to the diaphragm at a different point, whereby vibrations may be initiated at symmetrical points other than the apex of the diaphragm in any desired phase relation.

5 Referring now more particularly to Figures 1, 2 and 3, 1 designates an inner diaphragm, 2 an outer diaphragm, and 3 the driving means which may, for example, be a piezo-electric crystal device, such as Rochelle salt exhibiting the well known "hour glass" configuration; a stress plate 4 which may be of elastic metal such as steel is cemented or bolted, or both, to the top basal plane of the crystal 3, and driving rods 5 and 6 are suitably secured thereto at one end and at the other end to the apexes of diaphragms 1 and 2. The bottom basal plane of the crystal 3 is mounted as by cementing or bolting upon a bottom stress plate 7 to which is secured a support 8 passing through a suitable opening in the diaphragm 2.

10 A pair of electrodes, 9 and 10, diagrammatically shown, are also provided, associated with crystal 3. These electrodes may be of any desired form, but preferably one will consist of an equatorial belt of conducting material such as metal foil or graphite paint extending around the outer surface of the crystal parallel to and intermediate the top and bottom basal planes. The other electrode may be one or both of the plates 4 and 7, or may alternatively be an internal electrode such as a bolt passing through the crystal.

15 35 Application of electrical oscillations to the electrodes 9 and 10 causes a torsional vibration of the crystal 3 as a result of which the top stress plate 4 tends to rotate about the crystal axis. This rotation appears as substantially reciprocating motion of the driving rods 5 and 6, which sets into vibration the apexes of the diaphragms 1 and 2, thereby causing the propagation of stress waves toward the peripheries of these diaphragms, which peripheries may be suitably secured together, as by cementing, or left free. In any event, by reason of the adjacent position or physical contact of the peripheral edges of diaphragms 1 and 2, as well as by reasons of the reaction of the air confined between these diaphragms, a relatively different mode of vibration is obtained from that which would be obtained where either of the diaphragms alone operated in unconfined air.

40 50 55 Referring now more particularly to Figures 4 and 5, I have shown an arrangement in which the driving force is applied to points other than the apex of the diaphragm 2. In this instance, I provide a plurality of driving means such as piezo-electric crystal devices, 16, 17, 18 and 19, each provided with a base stress plates 20, 21, 22 and 23 respectively, and top stress plates 24, 25, 26 and 27 respectively, suitably held in position upon the crystal by means of bolts 28, 29, 30 and 31 re-

spectively passing through the crystals and the top and bottom stress plates. In addition, the stress plates may be cemented to the crystal if desired. The stress plates are all supported from a suitable central support 15 forming an extension of the base 8, and in this instance, passing into the interior space between the diaphragms through an opening at the apex of the diaphragm 2. This support 15 is preferably square in cross section and is extended to permit of the bolting or cementing of the apex of the diaphragm 1 thereto. Each of the base plates 21, 22 and 23, is secured in position as shown in Figures 4 and 5, by means of suitable bolts and associated nuts 32 and 33, which anchor the crystals 16, 17, 18 and 19, in position as shown. The top stress plates 24, 25, 26 and 27, terminate in suitable driving means 42, 43, 44 and 45 respectively, secured to the diaphragm 2 in any suitable manner as by bolting or cementing. The diaphragm is preferably reinforced at the points of contact by suitable disks 50, 51, 52, 53, suitably secured thereto, which serve to apply the driving force over a relatively larger surface of the diaphragm than would be the case were they omitted. The crystal 16 is provided with electrodes 34 and 35, crystal 17 with electrodes 36 and 37, crystal 18 with electrodes 38 and 39, and crystal 19 with electrodes 40 and 41, of any suitable type as heretofore described. The electrodes may be connected in any desired manner so that each of the driving heads 42, 43, 44 and 45 operates in phase, or out of phase with any other by connecting the electrodes similarly or dissimilarly: for example, if the internal bolts 28, 29, 30 and 31 constitute one electrode of crystals 16, 17, 18 and 19 each of these bolts may be connected together and to one source of the oscillations for driving the diaphragm. If the other electrodes 35, 37, 39 and 41, of each crystal are formed by a loop of conducting material about the crystal, each of these may be connected together and to the other terminal of the source, in which case the driving heads 42, 43, 44 and 45 will operate in phase, and the stress waves set up at points of connection of each of these driving heads to the diaphragm 2, will be the same. If, on the other hand, the connections to electrodes of crystals 16 and 18 be reversed, the stress waves initiated at points 42 and 44 will be out of phase with those initiated at points 43 and 45. It will be seen that by connecting the various crystal electrodes as desired to obtain the desired phase relation of vibrations in various parts of the diaphragm and as modified by the reaction of the diaphragm 1 and the air confined therebetween, a considerable number of modes of vibration may be obtained, and a considerable number of variations in frequency response may be obtained.

50 55 60 65 70 75 80 85 90 95 100 105 110 115 120 125 130 135 While I have shown and described certain

preferred forms of my invention, it will be apparent that modifications and changes may be made without departing from the spirit and scope of my invention, as will be understood by those skilled in the art.

5 I claim:

1. A loud speaker comprising a pair of conical diaphragms of different altitudes having their peripheries secured together and their apexes disposed on the same side of the peripheral plane but spaced apart and driving mechanism disposed between the apexes and connected thereto for imparting vibrations to each of said diaphragms.

15 2. A loud speaker comprising a pair of conical diaphragms of the same diameter but different altitude secured with their peripheries adjacent to each other and their apexes spaced apart on the same side of the peripheral planes and driving mechanism disposed between the apexes and connected thereto for imparting vibrations to each of said diaphragms.

25 3. A loud speaker comprising a pair of conical diaphragms having their peripheries of substantially the same diameter and secured together and having their apexes disposed on the same side of the peripheral plane and spaced apart and driving apparatus disposed within the space defined by the two cones and operatively connected to both of said diaphragms.

35 4. A loud speaker comprising a pair of conical diaphragms having a different solid angle at the apex, each of said diaphragms being mounted with their peripheries adjacent each other and driving mechanism disposed between the apexes and connected thereto for imparting vibrations to each of 40 said diaphragms.

45 5. A loud speaker comprising a pair of conical diaphragms having a different solid angle at the apex and mounted with their peripheries adjacent each other, and having the apexes disposed on the same side of the peripheral plane and driving mechanism disposed between the apexes and connected thereto for imparting vibrations to each of 50 said diaphragms.

55 6. A loud speaker comprising a pair of conical diaphragms mounted with their peripheries adjacent and their concave sides facing the same direction and means for driving said diaphragm, said means being housed entirely within the area enclosed by said diaphragms.

60 7. A loud speaker comprising a pair of conical diaphragms mounted with their peripheries adjacent and their concave sides facing the same direction and means for driving said diaphragms, said means being included entirely in the space between said diaphragms and links extending from said 65 means in opposite directions and connected

to the apexes of said diaphragms for simultaneously driving said diaphragms.

8. A loud speaker comprising a plurality of cone diaphragms of substantially the same diameter but of different altitude mounted with the peripheries adjacent and with the apexes disposed upon the same side of the peripheral plane and means for driving said diaphragms, said means being contained entirely in the space between said diaphragms 75 and means for applying the driving force developed by said driving means to said diaphragms at a plurality of points.

9. A loud speaker comprising two spaced conical diaphragms having different slopes, 80 one of said diaphragms being disposed at least partly within the other and a driving mechanism disposed in the space between said diaphragms and operatively connected to both of said diaphragms.

Signed at New York in the county of New York and State of New York this 16th day of March A. D. 1927.
